INSTRUMENT-ACTUATING DEVICE FOR KNITTING-MACHINES.

1,212,568.

Specification of Letters Patent. Patented Jan. 16, 1917.

Application filed August 30, 1915. Serial No. 47,951.

To all whom it may concern:

Be it known that I, ROBERT W. SCOTT, a citizen of the United States, and resident of Boston, in the county of Suffolk and State 5 of Massachusetts, have invented new and useful Improvements in Instrument-Actuating Devices for Knitting-Machines, of which the following is a specification.

My invention relates to knitting machines 10 having devices intended to be operated at regular intervals in the production of the fabric, as at recurrent courses separated by a plurality of courses during which the device is not operative, and having further 15 means for rendering the device idle or operative in the above stated manner.

I shall describe my improvement in connection with a needle cam adapted to be actuated at intervals of a plurality of courses 20 to clear the loops beneath the latches of certain abnormal needles, as one instance only of an instrument desired to be rendered inoperative for a season and thereafter to be rendered alternately operative and inoperative 25 at short periods; but many other obvious uses will occur to those skilled in the art.

One object of my invention is to provide a device of this nature which may be left in 30 either of its adjusted positions during a season of idleness, as predetermined by the mechanism.

In the accompanying drawings, Figure 1 is a right side elevation of a knitting machine showing so much of the mechanism as is necessary to enable my new devices to be understood; Fig. 2 is a plan; and Fig. 3 is a detail section on the line 3—3 of Fig. 1.

Referring to Fig. 1, in machines of the 40 type illustrated the driving and control mechanism may include a power shaft 30 through which the machine is driven, and a pattern or cam shaft 80 carrying pattern surfaces to determine the orderly operation 45 of the parts. The driving devices may include a shaft 55 actuated from the drive shaft 30 by a pinion on said shaft and a gear 65 rotating at a rate less than the rate of shaft 30. The rotary element of the knitting head, not shown, may rotate in unison with the shaft 30 which is driven by the pulley 47, the gear 65 rotating at a predetermined ratio with respect to the rate of the knitting head, for instance making one revo-

lution to each four revolutions of the knitting head.

The device to be adjusted may be any instrument, such as a clearing cam 416, for instance such a cam employed to clear the latches of long-latched needles distributed 60 among the normal needles, and I may provide a carriage for such a cam 416, consisting of a horizontal bent lever 420 pivoted at E, said lever having a depending portion 423 and being spring-held by a tension 65 spring 426, so that under the tension of said spring it tends to rock upon the pivot E to withdraw the cam 416 to an outer, inoperative position with respect to the needles with which it co-operates. As described and 70 claimed in my application Serial No. 853,053 filed July 25, 1914, such a lever 420 and cam 416 may be rocked about the pivot E at intervals of a plurality of rotations of the rotary element of the knitting head by means 75 of cams *a* and *b* adjustably fastened on the face of the gear 65, reacting with a plunger carried by the depending part 423 of the lever 420, when permitted by connection such as the bell-crank lever 110 co-operating with 80 pattern indications carried by the shaft 80.

When the cam 416 is desired not to be withdrawn from its inner active position for a time, the lever 110 is caused to move the depending portion 423 outward to take the 85 plunger out of range of the cams *a* and *b*, and to hold the cam 416 in its inner operative position with respect to the needles. As explained in my said application, when at the end of a cycle of operations or for other 90 purposes, it was desired to cease operating the cam 416 but at the same time to retain it in its outer inoperative position, the machine was organized to stop when the plunger was opposite the gap between cams *a* and 95 *b*, the lever 110 at the same time being released to permit spring 426 to remove the plunger inward into the gap between the cams, but not out of their path.

I shall now describe means for controlling 100 the operation of a pattern-controlled device such as the lever or carrier 420, so as to predetermine its operation at short intervals corresponding to revolutions or parts of revolutions of the rotary element of the machine, and automatically to bring the device 105 to rest in one or in another position, for instance in the construction shown with the

cam 416 in its inner position in operative contact with the needles or with the cam 416 in its withdrawn outer position, and out of contact with the needles. I have so organized my devices as to render this positioning of the member operated independent of the movement of its actuating device, such as cams on gear 65, so as not to require the machine to be brought to a stop to enable the cam 416 or the like to be rendered inoperative. The actuating device 65 may as before be provided with cams *a* and *b* to encounter and move a plunger or follower member 424 suitably fastened for adjustment to the lever 420. As illustrated in Figs. 1 and 3, plunger 424 terminates in a hook *k'* having an arched opening *k* large enough freely to pass the cams *a* and *b* when in the position illustrated in Fig. 3 with respect to the gear 65, which gear is provided with an annular groove *h* to receive the point *k'* of the follower member when the lever 420 is to be so positioned as to hold the cam 416 or the like in its outer idle position. When the lever 420 is to be operated by the cams *a* and *b*, the inner position of the plunger 424 under the stress of spring 426 is so fixed by the connection 110 as to bring the part *k'* of the plunger 424 into the path of the cams *a* and *b*, and when the lever 420 is to be so positioned as to leave the cam 416 idle but in its inner operative position, plunger 424 is positioned outwardly as illustrated in Fig. 1 and in dotted lines in Fig. 3. To produce the above-indicated movements, the shaft 80 carries in suitable relation to the other indications controlling the cycle of operations of the machine high cams *c*, *d*, and *e* reacting with the lever 110 to hold the plunger 424 in its outward position, and suitable intermediate concentric surfaces *f* and *g* to hold the plunger 424 so that the part *k'* is encountered and moved by the cams *a* and *b*, and a low part *m*, which will permit the lever 110 to move under the stress of spring 426 to position the part *k'* in annular groove *h*. The low part *m* of the pattern cam so made up and carried by the shaft 80 may be associated with a cam lug 106 co-operating with a belt shipper to stop the machine, so as to permit the needle-actuating cam 416 to be withdrawn prior to stoppage of the machine. One use of this arrangement is to withdraw the cam 416 when the needles are to be leveled to receive a transferred fabric section during stoppage of the machine.

It will be observed that with the described devices, the machine and the gear 65 may be permitted to rotate during any desired time, as for the operation of leveling devices.

While I have described a preferred arrangement in which the pattern surface controlling lever 110 is comprised of cams *c*, *d*, *e*, *f* and *g* on shaft 80, it is obvious that the

pattern surface for this purpose may be attached to any part of the machine moved during the making of the product in any convenient manner.

While I have described my invention in connection with a specific movable instrument to be operated by it, this specific embodiment is illustrative only, my invention relating to means for operating any of the genus of worked parts or instruments for producing changes in the knitting by interfering with any of the agencies of the machine, of which the instance given is one species only.

What I claim is:

1. A knitting machine having in combination a movable member or instrument, an actuating device therefor moving in a fixed path, a follower for said actuating device forming a part of and movable with said movable member, and pattern-controlled means for shifting said follower from said path into idle positions out of contact with said device on each side of said path.

2. In a knitting machine, the combination of a movable member, an actuating cam therefor rotating in a circular path, a follower for said actuating cam connected to said member, and pattern controlled means for shifting said follower from said circular path into idle positions on each side thereof.

3. A knitting machine having a frequently actuated part for effecting changes in the knitting, an actuating device rotating in a circular path, and a follower forming part of and movable with a connection between said actuating device and said part, in combination with means for positioning said follower in said circular path, wholly inside of said path, and wholly outside of said path, at predetermined times, whereby respectively to actuate and to render idle in two different positions said frequently actuated part.

4. A knitting machine having a frequently actuated part such as a movable needle cam, an actuating cam rotating in a circular path, and a hooked follower forming part of a connection between said actuating device and said part, having an opening therein, in combination with means for positioning said follower with its free end in said circular path, with its opening in said path, and with its free end outside of said path, at predetermined times, respectively to actuate said part, and to hold said part idle in two different positions.

5. A knitting machine having a member adapted to be actuated at frequent intervals, in combination with means for holding said member in different idle positions comprising a carrier for said member, an actuating cam for said carrier rotating in a circular path, a hooked follower on said carrier movable in the plane of rotation of said cam,

and pattern means for positioning said follower to contact with and be moved by said actuating cam, and in any of a plurality of idle positions in said plane of rotation and 5 out of operative contact with said cam.

6. In a knitting machine, the combination of a movable member such as a needle-cam, an actuating device therefor moving in a fixed path, a follower for said actuating device connected to and movable with said needle cam, a pattern surface, and a connection between said pattern surface and said follower for limiting movement of said follower in one direction, said surface having 10

intermediate levels for determining actuation of said follower, and high and low parts for holding said follower idle in different positions with respect to the path of said actuating device. 15

7. In an actuating device for knitting machines, the combination of a rotating actuating member having cams thereon in an annular space, with a follower movable radially of said rotating member having an arched part adapted to bridge said annular space. 20 25

Signed by me at Boston, Massachusetts, this twenty-seventh day of August, 1915.

ROBERT W. SCOTT.
